UNITED STATES PATENT OFFICE

2,443,805

BUCKLE

Samuel Segal, New York, N. Y.

Application April 11, 1944, Serial No. 530,478

5 Claims. (Cl. 24—74)

1

The invention is a buckle and the object thereof resides in the provision of an indicia carrying bridge member disconnectably retained between resilient arms of the U-shaped hasp of the buckle and characterizing means for concealing the free end of strap fastening means removably threaded into the buckle. Another object of the invention is realized in the utilization of a transverse brace or bar disengageably interlocked between the arms of the hasp for sustaining the bridge member between the arms of the hasp against displacement. Other objects and functional and structural features of the invention will appear from the following detailed specification considered in the light of the accompanying drawings wherein:

Fig. 1 is a perspective view of the buckle according to my invention.

Fig. 2 is a longitudinal view of the buckle partly shown in section.

Fig. 3 is a longitudinal sectional view on the line 3—3 of Fig. 2.

Fig. 4 is an inside perspective view of the buckle, and

Fig. 5 is an exploded view of the parts of the buckle.

According to the invention, the buckle generally denoted B comprises a U-shaped hasp H of metal or plastic material having the spaced arms 10 integrally merged with the brace or bar 11 having a recess 12 for removably receiving the prong or lip 13 of the tongue 14 extending from the brace 15 having pintles 16 rotatably and removably receivable in the aligned openings or bearing 17 in the resilient and spaced arms 10 of the hasp.

The proximal or anterior portions 18 of the arms 10 are relatively thicker than the distal or posterior portions 19, thus characterizing aligned shoulders 20 and adjacent to but spaced from the latter are the fixed positioning pins 21 adapted to be received by the aligned and spaced notches 22 in the depending sides 23 of the channeled shaped bridge member 24 having embossed or fastened thereon suitable indicia 25. By this arrangement, the indicia carrying or bridge member may be quickly assembled with arms of the hasp and desirably retained at one end by the fixed positioning pins 21 and against the stop shoulders 20 which limit the displacement of the bridge member towards the proximal part of the hasp.

With the bridge member 24 clasped between and straddled by distal portions 19, aligned distal notches 26 of the depending sides 23 are in aline-

ment with the distal and aligned openings or bearings 27 of the attenuated clamping portions 19. Thereafter a locking or bar member 28 is inserted between the distal portions 19 in such a manner that the pintles 29 are projected through the notches 26 of the bridge member 24 and into aligned bearings 27. This may be accomplished by first spreading the distal portions 19 slightly apart. However the resilient arms 10 immediately retract to grasp and hold the relatively flat inner surfaces of portions 19 against the relative flat outside surfaces of sides 23 of the bridge member 24.

It is also apparent that the pins 21 and pintles 29 closely straddle the notched portions of the depending sides 23 thus securely holding the latter between the arms 10 and against the stop shoulders 20. Hence the rotatable or swiveled locking bar 28 retains bridge member 24 in its appropriate set position.

With the present arrangement the bridge member may be quickly removed from the hasp. This is accomplished by spreading the resilient distal portions 19 apart, thus freeing the pintles 29 from the bearings 27 and therefore the rotatable locking bar may be removed from the notches 26. It follows that the bridge member 24 is unlocked and can be readily withdrawn from the positioning pins 21 and if desired be replaced by another bridge member carrying different indicia.

About the rotatable and removable locking bar 28 may be appropriately looped one end of a two ply and stitched strap member 30 to which may be attached a wrist watch 31 also secured to a perforated two ply and stitched strap member 32 adapted to be threaded under the front brace or bar 11 and between arms 10 whereupon lip 13 may enter a pair of aligned perforations 33 after which this strap member 32 is passed over the rockable or rotatable brace 15 and subsequently threaded under the bridge member 24 and between the depending sides 23 thereof whereby terminal or flap 34 of the strap member 32 may be positioned against the rear portion of the loop 35 of the strap member 30 about the rockable locking bar 28.

Thus according to the invention the free end or flap 34 of the strap member 32 is retained behind the buckle and concealed by the bridge member 25, thus doing away with an unsightly freely disposed flap.

Various changes may be made in the form and construction of the embodiment disclosed

without departing from the invention or sacrificing the advantages thereof.

I claim:

1. In a buckle, a hasp having spaced arms comprising proximal and distal portions defining alined shoulders, a brace integrally merged with said arms, a bridge member having spaced sides interposed between said distal portions and including spaced notches, pins extending from said arms for reception by said notches to position said bridge member between said arms, a rotatable bar removably interlocking with said member and with said distal portions, a rotatable brace between said arms and having a lip to cooperate with said hasp, and said shoulders limiting the displacement of said bridge member relative to said hasp.

2. In a buckle, a hasp having spaced resilient arms comprising alined proximal and distal attenuated portions defining alined and spaced shoulders, a brace integrally merged with said arms, a bridge member having spaced sides interposed between said distal portions and including a pair of distal and spaced notches and a pair of proximal and spaced notches, pins extending from said distal portions for reception by said pair of proximal notches to position said bridge member between said arms, a rotatable bar disposed within said bridge member and having pintles for removable reception by said pair of distal notches and for removable and rotatable reception by said distal portions to maintain said bridge member between said arms, and a rotatable and removable brace between said arms and having a lip to cooperate with said hasp.

3. In combination, spaced arms having spaced bearings, a bridge member interposed between said arms and having posterior and anterior notch means, pin means extending from said arms and removably receivable in said anterior notch means to preclude displacement of said member transversely of said arms, and a bar hav-

ing pintles removably receivable in said posterior notch means to preclude longitudinal displacement of said member relative to said arms and removably receivable in said bearings to rotatably sustain said bar relative to said arms.

4. In combination, a hasp having spaced arms including spaced pins and spaced bearings, a bridge member interposed between said arms and having anterior notches removably interlocking with said pins and having posterior notches, a bar interposed between said arms and having pintles removably interlocking with said posterior notches and with said bearings, and a brace rotatably carried by said arms and having a lip cooperating with said hasp.

5. In a buckle, a hasp having spaced arms including alined bearings, a brace integrally merged with said arms, a bridge member interposed between said arms and having anterior and posterior notched portions, means carried by said arms for disengageably interlocking with said anterior notched portion, a bar interposed between said arms and having means to removably interlock with said posterior notched portions and removably disposed and rotatably guided in said bearings, and a brace rotatably carried by said arms and having a lip cooperating with said first mentioned brace.

SAMUEL SEGAL.
